UNITED STATES PATENT OFFICE.

MURRELL R. DE FRANCE, OF BELLEVUE, PENNSYLVANIA.

BRAKE SHOE.

Application filed October 16, 1924. Serial No. 743,937.

To all whom it may concern:

Be it known that I, MURRELL R. DE FRANCE, a citizen of the United States, residing at Bellevue, in the county of Allegheny and State of Pennsylvania, have invented a new and useful Improvement in a Brake Shoe, of which the following is a specification.

This invention relates to brake shoes and particularly to a brake shoe having a pressed sheet metal shell together with a filling of frictional material to be used in exerting a braking effect on the wheels of railroad cars and similar vehicles.

In such a brake shoe it is entirely the filling of frictional composition which performs the braking function. These various frictional compositions have a definite crushing strength but have a very limited tensile strength. Hence it follows that the shell must be of sufficient weight and strength to prevent pulling apart or distortion of the brake shoe, and of such weight and strength that the brake shoe shell will hold its arc and retain the composition filling in place until the composition is entirely worn out.

For a number of years brake shoes of the above type have been manufactured and used, the shell being pressed from a sheet of metal of uniform thickness throughout, that is to say the back ends and sides of the shell being of the same thickness. This shell had one serious defect. On long application of the brakes to a railroad car going down mountain grades the sides of the shell would become red hot. Upon the release of the brakes the shell would cool, heat up again on the next application, and this cooling and heating in time would temper the shell to a hardness that would cut or groove the wheel. This shoe never came into general use and its manufacture has been abandoned.

An attempt to remedy this defect may be found in patent to Murrell R. De France No. 1,114,343; in which the sides of a pressed brake shoe shell are tapered and corrugated vertically. In such patent it is stated that the metal in the side walls cannot be reduced in thickness throughout their entire height on account of weakening the walls so that they would not have sufficient strength to hold the frictional composition of the brake shoe in position. Since the date of such patent, however, it has been discovered how

small a part the side walls of a shell function in the support of the brake shoe as a whole. With the form of shell shown in such patent, it is found that as the frictional composition wears away to expose the tire of a railway car wheel to the thicker portion of the side walls of the shell, there is a tendency for these walls to heat, temper, and score the rim of the wheel.

Later the thickness of the sheet of metal from which the shell is pressed was reduced to a point where it was thought the heating of the sides would be eliminated, and the sides of the shell were reticulated as in patent to Murrell R. De France No. 1,303,173. This lighter weight shell became distorted in use, because the back did not have enough strength to retain the lug by which the shoe is attached to the hanger, and because the ends of the shell were pulled off when the brake shoe became worn down by continued use. To remedy these defects the back of the shell was then corrugated, and an additional reinforcing plate attached to the back, thus adding to the cost of production and assembling, and it is still a question whether the metal in the sides of the shell had been reduced to a point where the shoe will meet all classes of railroad service without damage to the wheel.

In the present invention it is desired to provide a pressed metal brake shoe shell with a back and ends of comparatively great thickness and strength, in order that it may be able to withstand the thrusts to which it is subjected without distortion and to prevent the shoe from being torn, or the lug torn loose, when the filling of frictional composition is worn thin. In addition to making the back and ends of the shell of a strength sufficient to prevent the brake shoe from being torn apart it is desired that it be in itself of sufficient weight and strength to hold its arc, and consequently the arc of the brake shoe as a whole, without any supporting effect from the sides of the shell.

If the back and ends of a pressed metal brake shoe shell be of the desired strength the sides of the shell may be as thin as paper, and serve merely to protect the block of frictional composition, forming the filling material of the brake shoe, from chipping or breaking during handling prior to the attachment of the brake shoe to a vehicle. Under such circumstances the sides

of the pressed metal shell perform no material supporting or braking function; and, being so thin, would wear faster than the composition filling, thus eliminating all danger of heating and tempering with consequent cutting or other injury to wheels.

Brake shoes for railroads are made to specified dimensions, with a suitable specified lug by which they are attached with a key to a brake shoe hanger of specified dimensions. On each end of the hanger there are two fingers or guides that engage with a button or projection near each end of the shoe. This is to hold the shoe in alignment with the tread of the wheel.

The lug for receiving the key of the brake shoe hanger must be made separately and attached to the back of the brake shoe shell. It is extremely advisable that this lug be so formed as to engage the key of the brake shoe hanger firmly.

If the sheet of metal from which the brake shoe shell is pressed is heated prior to such operation, the buttons to engage the fingers or guides of the hanger may be pressed out to specified dimensions, no matter how thick the back of the shell. They have never, however, been pressed out from a cold sheet to specified dimensions. It is desirable, therefore, to provide a separately formed and attachable button, which may be clinched to the back of the shell, and thus save the cost of heating the sheets.

An object of the invention is to provide a brake shoe shell, pressed from a single integral cold blank, which has a back of relatively great thickness and strength together with sides which are uniformly thin throughout their entire vertical extent.

Another object of the invention is to provide suitable buttons and lug to contact the fingers or guides of the brake shoe hanger and to firmly engage the key thereof.

A still further object of the invention is to provide a pressed brake shoe shell in which the form of the shell provides for the flow and distribution of surplus metal during the operation of pressing the shell.

In the accompanying drawings Figure 1 is a vertical sectional view through the brake shoe of the present invention; Figure 2 is a bottom plan view thereof; Figure 3 is a cross sectional view thereof taken on the line 3—3 Figure 1; Figure 4 is an end elevation of the brake shoe; Figure 5 is a top plan view of the blank from which the brake shoe is being pressed; Figure 6 is a side elevation of the blank; and Figure 7 is a cross sectional view through the blank taken on the line 7—7 Figure 5; Figure 8 is a cross sectional view on the line 8—8 Figure 1, showing one of the end lugs of the brake shoe; and Figure 9 is a bottom plan view of the blank from which the lug for receiving the key of the brake shoe hanger is pressed.

In the drawings the reference numeral 1 designates the brake shoe filling of frictional composition, and 2 the brake shoe shell generally. The filling composition may be of any desired nature, such as a composition of fibrous material, coke, and a binder, either with or without a friction increasing material such as metallic borings or filings.

The brake shoe shell proper comprises a back 3, end walls 4, and side walls 5, all of which are pressed into form from a single integral blank 6.

In the brake shoe of the present invention the blank 6 is a rolled sheet with a central portion 6^a of considerably greater thickness than the side portions, or webs 6^b, which extend longitudinally therewith. The back 6^a of the blank is punched or cut to provide apertures 7 along the transverse median line of the blank, for the reception of the main lug which receives the brake shoe hanger; and is provided adjacent each extremity of the blank with slots 8 cut or punched for the reception of the end lugs or buttons of the brake shoe.

In forming the brake shoe shell 2, the cold blank 6 is subjected to a suitable die pressing operation. In such operation the longitudinal central portion 6^a of the blank becomes the back 3 of the brake shoe shell, while the side or web portions 6^b of the blank become the sides of the brake shoe shell.

The end walls 4 of the shell are formed from the areas of the portions 6^a of the blank which lie adjacent the extremities thereof. These end walls 4 must also comprise surplus metal from the side portions 6^b. In order to permit the flow of this metal from the sides and to distribute the same in the end wall of the shell, and also in order to increase the strength of the end walls, the dies in which the blank is pressed are preferably formed to produce vertical corrugations in the end walls of the shell. This takes up the surplus metal, and saves wear on the necessarily costly dies.

The brake shoe shell 2 thus has its side walls 5 of materially less thickness throughout their entire vertical extent than is the back wall 3 of the shell, thus providing a shell having a strong back and ends, with sides which comprise a minimum quantity of metal.

The main lug 9 for receiving and engaging the key of the brake shoe hanger is secured to the shell prior to the pressing of the filling of frictional composition thereinto, by extending the extremities of the side walls, or tongues of the lug downwardly through the slots 7 in the back of the shell and bending upwardly the portions of these tongues or sides which project into the body of the shell. In order that it may grip and firmly engage the key of a brake shoe

hanger, this lug is shown as provided with sharp teeth or protuberances 9^a on the under surface of the top portion of the lug.

As shown in Figure 9 of the drawings, these 5 teeth 9^a may be initially formed as ridges in punching the blank 9^b for the lug by slightly upsetting a small amount of metal along the side edges of the blank, as in the regions 9^c. The final operation of pressing the lug then 10 converts these upset regions into the teeth 9^a of the lug.

With brake shoe shells pressed from sheet metal, the end lugs, or buttons, of the brake shoe have previously been provided by slotting 15 the back of the shell adjacent the extremities thereof, or heating the blank, and pressing out upwardly extending tongues, which receive a filling of the frictional composition in pressing the same into the shell, 20 to form buttons. Since, however, the present integral shell comprises no reinforcement for its back, it is desirable to weaken the back as little as possible. For this reason as well as for reasons of manufacturing 25 expediency, the slots 8 are provided, and simple lugs 10 are secured to the back of the shell by means of tongues 10^a, which extend downwardly through the slots and are bent upwardly against the inner surface of the 30 back 3.

The brake shoe of the present invention approximates the simplicity of manufacture, and all the specified dimensions, of a cast 35 brake shoe, while retaining all the advantages of cheaper production cost incident to the pressed shell and filling composition type of shoe. The thickness of the back wall of the brake shoe shell, and the relative thinness of the side walls throughout their 40 entire vertical extent, give a maximum of resistance to breaking or distortion of the shoe during any stage of its gradual wearing away in use, while presenting a minimum of sheet metals to the tire of a wheel 45 with which the brake shoe is used.

The relatively great thickness, and the corrugated form of the end walls of the shell also assist materially in supporting the back and assisting to maintain the arc of 50 the brake shoe.

What I claim is:

1. In a brake shoe having a filling of composition, a containing plate having a thick central portion extending substantially the 55 length thereof and thinner side portions along the edges thereof, said plate being pressed to form a dish shaped container the ends of which are corrugated vertically to take up surplus metal of the plate.

2. In a brake shoe having a filling of composition, a containing plate having a thick central portion extending substantially the 60 length thereof and thinner side portions along the edges thereof, said plate being pressed to provide a dish shaped container

the relatively thin sides of which are formed by bending the plates along the lines formed by the change of thickness in the plate.

3. In a brake shoe having a filling of composition, a containing plate having a thick 70 central portion extending substantially the length thereof and thinner side portions along the edges thereof; said plate being pressed to provide a dish shaped container the relatively thin sides of which are formed 75 by bending the plates along the lines formed by the change of thickness in the plate, and the ends of which are corrugated vertically to take up surplus metal of the plate.

4. In a brake shoe having a filling of composition and a pressed metal shell embracing the same, a metallic shell pressed from a single integral blank which has a relatively thick back wall and relatively thin side walls of uniform thickness throughout their 80 vertical extent, and a separately formed lug attached to the back of the shell and having in the key way thereof teeth for firmly 85 engaging the key which connects the brake shoe to its hanger.

5. In a brake shoe having a filling of composition and a pressed metal shell embracing the same, a metallic shell pressed from a single integral blank which has relatively thick back and end walls and relatively 90 thin side walls of uniform thickness throughout their vertical extent, and a separately formed lug attached to the back of the shell and having in the key way thereof 95 teeth for firmly engaging the key which connects the brake shoe to its hanger.

6. In a brake shoe having a filling of composition and a pressed metal shell embracing the same, a metallic shell pressed from a single integral blank which has relatively thick 105 back and end walls and relatively thin side walls of uniform thickness throughout their vertical extent, the end walls of the shell being corrugated vertically thereof and a separately formed lug attached to the back of the shell and having in the key way thereof teeth 110 for firmly engaging the key which connects the brake shoe to its hanger.

7. In a brake shoe having a filling of composition and a pressed metal shell embracing the same, a metallic shell pressed from a single integral blank which has a relatively thick back wall and relatively thin side walls 115 of uniform thickness throughout their vertical extent, separately formed end lugs or buttons for contacting the fingers of a brake shoe hanger attached to the back wall of the shell, and a separately formed lug attached to the back of the shell and having in the key way thereof teeth for firmly engaging the key which connects the brake shoe to its hanger.

8. In a brake shoe having a filling of composition and a pressed metal shell embracing 120 the same, a lug for receiving the key of a 125

brake shoe hanger formed separately from the shell and adapted to be attached to the back thereof, said lug having in the key way thereof teeth for firmly engaging the key which connects the brake shoe to its hanger.

9. In a brake shoe having a filling of composition and a pressed metal containing shell embracing the same, a metallic shell pressed from a single integral blank which has a relatively thick back and relatively thin sides of uniform thickness throughout their entire vertical extent, the change in thickness between said back and sides being abrupt and along the lines of change of direction between the back and sides, and the ends being corrugated vertically to take up surplus metal in pressing.

10. In a brake shoe having a filling of composition and a pressed metal containing shell embracing the same, a metallic shell pressed from a single integral blank which has a relatively thick back and relatively thin sides of uniform thickness throughout their entire vertical extent, the change in thickness between said back and sides being abrupt and along the lines of change of direction between the back and sides, and the ends being corrugated vertically to take up surplus metal in pressing.

20
25

In witness whereof, I hereunto set my hand.

MURRELL R. DE FRANCE.
